[57] CLAIM

The ornamental design for a motor drive, as shown.

DESCRIPTION

FIG. 1 is a perspective view of a motor drive showing our new design;

FIG. 2 is a further perspective view thereof;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a top plan view thereof; and,

FIG. 8 is a bottom view thereof.

The broken line showing of a motor with mounting studs and nuts is for illustrative purposes only and forms no part of the claimed design.

The top portion of the claimed design not shown in FIG. 7 is plain and unornamented and forms no part of the claimed design.
